(57) **CLAIM**

The ornamental design for a USB-C surface mount connector, as shown and described.

DESCRIPTION

FIG. 1 is a top, front, and right side perspective view of a USB-C surface mount connector;

FIG. 2 is a front view thereof.

FIG. 3 is a back view thereof.

FIG. 4 is a left side view thereof.

FIG. 5 is a right side view thereof.

FIG. 6 is a top view thereof; and,

FIG. 7 is a bottom view thereof.

The broken lines are for the purpose of illustrating environmental structure and forms no part of the claimed design. The brackets and broken line broken away symbols in the drawings indicate the broken lines and appearance of any portion of the article between the break lines forms no part of the claimed design.

1 Claim, 7 Drawing Sheets
